Wm H. Page & Co. of the same place.

Letters Patent No 1933 Dated April 19th, 1864.

Design for Ornate Letters.

The schedule referred to in these Letters Patent and making part of the same.

To all whom it may concern:

Be it known that I, William H. Page, of the town of Norwich, in the County of New London and State of Connecticut, have invented or produced a new and original design of letters styled ornate; and I do hereby declare that the accompanying drawing is a full and exact representation of the same.

What I claim as new and desire to secure by Letters Patent is
The design for the alphabet as shown and described.
